LUBRICATING OIL PREPARATION

Herman P. Lankelma, Cleveland, Ohio, assignor to
 The Standard Oil Company, Cleveland, Ohio, a
 corporation of Ohio

No Drawing. Original application September 4,
 1936, Serial No. 99,450. Divided and this ap-
 plication June 7, 1938, Serial No. 212,292

8 Claims. (Cl. 252—51)

This invention relates to lubricating oils, and
 more particularly the beneficiation of mineral
 lubricating oils which are subject to high tem-
 perature usage; and it is among the objects of
 5 the invention to provide an oil which is especially
 durable in high temperature usage, as in internal
 combustion engines, etc.

To the accomplishment of the foregoing and
 related ends, the invention, then comprises the
 10 features hereinafter fully described, and par-
 ticularly pointed out in the claims, the following
 description setting forth in detail certain illus-
 trative embodiments of the invention, these be-
 15 ing indicative however, of but a few of the va-
 rious ways in which the principle of the invention
 may be employed.

A mineral lubricating oil stock of desired vis-
 cosity is treated by incorporation of a small
 20 amount of a hydro-compound from the group
 consisting of hydroquinine, hydroquinidine and
 hydrocinchonine. These compounds readily dis-
 solve and disseminate, and the amounts em-
 ployed may in general be from 0.001 to 5 per
 25 cent, and oil stocks of for instance 45-200 sec.
 at 210° F. Saybolt Universal may be treated.

As an example: 0.01 per cent of hydroquinine
 is incorporated in an oil of 50 sec. at 210° F. Say-
 bolt Universal, being thoroughly mixed.

Similarly with the other hydro-compounds.
 30 This application is a division of my applica-
 tion Ser. No. 99,450, filed Sept. 4, 1936.

Other modes of applying the principle of the
 invention may be employed, change being made
 35 as regards the details described, provided the fea-
 tures stated in any of the following claims, or
 the equivalent of such, be employed.

I therefore particularly point out and dis-
 tinctly claim as my invention:

1. A process of preparing lubricating oils,
 40 which comprises beneficiating a mineral oil ca-

pable of lubricating viscosity at high tempera-
 ture by incorporating therewith a small amount
 of a hydro-compound of the group consisting of
 hydroquinine, hydroquinidine, and hydrocin-
 chonine. 5

2. A process of preparing lubricating oils,
 which comprises beneficiating a mineral oil ca-
 pable of lubricating viscosity at high tempera-
 ture by incorporating therewith a small amount
 of hydroquinine. 10

3. A process of preparing lubricating oils,
 which comprises beneficiating a mineral oil ca-
 pable of lubricating viscosity at high tempera-
 ture by incorporating therewith a small amount
 of hydroquinidine. 15

4. A process of preparing lubricating oils, which
 comprises beneficiating a mineral oil capable of
 lubricating viscosity at high temperature by in-
 corporating therewith a small amount of hydro-
 cincinonine. 20

5. A lubricating composition comprising a
 mineral oil capable of lubricating viscosity at
 high temperature and a small amount of a
 hydro-compound of the group consisting of
 hydroquinine, hydroquinidine, and hydrocin-
 chonine. 25

6. A lubricating composition comprising a
 mineral oil capable of lubricating viscosity at
 high temperature and a small amount of hydro-
 quinine. 30

7. A lubricating composition comprising a
 mineral oil capable of lubricating viscosity at
 high temperature and a small amount of hydro-
 quinidine. 35

8. A lubricating composition comprising a
 mineral oil capable of lubricating viscosity at
 high temperature and a small amount of hydro-
 cincinonine. 40

HERMAN P. LANKELMA.
